METHOD OF COATING PISTON RING SEGMENTS
 Herbert F. Prasse, Town and Country, Mo., assignor to
 Ramsey Corporation, St. Louis, Mo., a corporation of
 Missouri

Filed June 4, 1964, Ser. No. 372,473
 1 Claim. (Cl. 29—156.4)

This invention relates to coated piston ring segments and to a method of making the same. More particularly, the invention relates to the making of rail rings, or ring segments, each having a thin, sharp-edged, outer coating of a wear-resistant material to impart to the rings a longer effective life in service.

It has heretofore been known, as in Patent No. 2,905,512, to provide piston rings with a wear-resistant, thin coating of molybdenum by spraying molybdenum metal against the outer surfaces of individual rings mounted on a backing arbor. In accordance with my present invention, however, the rings, or ring segments, are formed from a coil that has been coated with a wear-resistant material prior to separation into individual rings or segments.

Briefly, my method comprises providing a supply coil of a spirally wound elongated strip of a heat-hardenable steel alloy or other suitable metal or alloy, in the form of a relatively thin, flat ribbon, with the flat faces of the ribbon in superimposed relationship radially of the coil. A suitable length of such ribbon is then taken from said supply coil and is rewound into a tightly wound helical coil in which the thin edges of the ribbon form the inner and outer surfaces of the coil and the flat faces of the ribbon are pressed together into laterally confronting abutting relationship lengthwise of the coil.

Thereafter, the outer surface of a predetermined length of the coil, while supported edgewise on an arbor, is sprayed to apply to the edges of the ribbon a thin coating of a wear-resistant material selected from the group consisting of molybdenum, tungsten, tantalum and osmium. After finishing the coated surface, as by abrasion, to the desired thickness of coating, the turns of the coil are severed lengthwise of the coil to form individual rings or ring segments, each having a transverse gap and each having the requisite outer and inner dimensions for use in a piston ring assembly.

While the final rings, or ring segments are particularly adapted for use as rail rings in an assembly such as illustrated in the Cable Patent No. 2,768,038, the method of my invention is not intended to be limited to rail rings only. When used as rail rings, however, the unusually sharp lateral edges of the abrasion-resistant coating provided by my method greatly enhance the scraping effectiveness of the rings against the cylinder wall without any attendant damage from scuffing the wall as sometimes happens with chromium-plated rings.

It is therefore an important object of my invention to provide a new and improved method for the economical manufacture of piston rings and ring segments having thin outer edge coatings providing effective wear-resistant outer surfaces and scraping edges.

It is a further important object of this invention to provide a method for making piston rings and ring segments wherein the ring segments are formed from a spirally wound coil of a flat, thin ribbon of a suitable steel alloy, by winding a length therefrom edgewise into a tightly wound helical coil of the desired inner diameter dimension, spray coating the outer edge surface of the coil turns with a continuous thin layer of a wear-resistant material and severing the coil lengthwise to free the individual ring segments, each with a transverse gap therein and with an outer, thin, sharp-edged layer of the wear-resistant material.

2

It is a further important object of this invention to provide piston rings and ring segments having a thin, sharp-edged outer layer of a high melting point metal that imparts to the rings and ring segments particularly effective wear-resistant properties while at the same time improving their wall-scraping effectiveness in service.

Other and further important objects of this invention will become apparent from the following description of the accompanying drawings, in which like reference numerals refer to like parts, and in which:

FIGURE 1 is a broken, side or end elevational view, partly in section illustrating the first step of the method of my invention, wherein a length of the ribbon-like metal strip from which the rings are to be made, is withdrawn from a spirally wound coil forming a supply of such strip, and is rewound edgewise on an arbor into a helical coil of the desired dimensions;

FIGURE 2 is a side elevational view of the helical coil after removal from the arbor of FIG. 1;

FIGURE 3 is a top plan view partly broken away and in section, illustrating a further stage of my method in which the helical coil of FIG. 2 has been mounted on a supporting arbor and placed under endwise clamping pressure to facilitate finishing the coil to the desired outside diameter dimension, as by grinding or machining;

FIGURE 4 is an enlarged top plan view of the arbor of FIG. 3, or a similar arbor, also partly broken and in section, illustrating two further steps of my method in which the outer surface of the helical coil is first sprayed with a wear-resistant material, and then any excess of the sprayed layer is removed, as by grinding or machining, to leave a thin coating continuously thereover of the desired final dimension;

FIGURE 5 is a greatly enlarged fragmentary view, partly in section and partly in plan, illustrating the steps of severing the helical coil lengthwise thereof to form individual rings or ring segments, each with a transverse gap;

FIGURE 6 is a plan view, reduced in size, of a finished piston ring segment as produced by my method, suitable for use as a rail ring;

FIGURE 7 is an enlarged fragmentary cross-sectional view of a rail ring assembly in a piston ring groove with the piston ring assembly shown in relationship to the wall of a cylinder in which the piston is operating; and

FIGURE 8 is a fragmentary, perspective view of a mounting of the type with which my rail ring segments are adapted to be assembled.

As shown on the drawings:

The reference numeral 10 indicates generally a spirally wound coil of an elongated strip 11 of the metal or alloy from which the piston rings or ring segments are to be made. Said strip 11 is formed of a thin, flat ribbon having parallel planar surfaces 12 and thin edge surfaces 13 and 14. The coil 10 constitutes a supply coil of an indefinite continuous length of the strip 11 from which individual lengths of the strip are withdrawn for processing in the manner about to be described.

Preferably the strip 11 is a strip of a heat-hardenable steel in its drawn and hardened condition. Suitable hardenable steels are those having the specifications S.A.E. 1070 or 1050, but other hardenable steels and steel alloys can be used. A strip 11 of such drawn and hardened steel is wound up spirally on a spool 15 with the flat faces 12 of the strip in radially superimposed relationship.

In the first step of my method, a length of the strip 11, beginning with its free end 11a, is unwound from the spool 15 into a tight helix H upon a rotatable cylindrical arbor 16 of the proper diameter for imparting to the helically wound strip 11 the desired inner diameter. As shown, the axes of the spool 15 and the arbor 16 are parallel, thereby requiring a turning, as at T, of the ribbon in passing from

the spools to the arbor, but this turning can obviously be obviated by arranging the axes at right angles. On the arbor 16 the strip 11 is wound helically with the flat faces 12 of the turns in laterally confronting relationship and with the edge surface 13 forming the outer surface and the edge surface 14 forming the inner surface of the helix.

After a predetermined length of the strip 11 has been tightly wound on the arbor 16, a helix of the proper length is cut off, the ends of which are indicated by the reference numerals 11a and 11b. By uncoiling the helix slightly, as illustrated by the helix H' (FIG. 2) the inner diameter is increased sufficiently to permit the helix to be positioned on an arbor 25. When released, the helix will contract to hug the arbor.

The arbor 25 (FIG. 3) may be used as a sizing arbor if the material as supplied requires a grinding or machining operation at this state. Otherwise, this step can be omitted.

Said arbor 25 comprises a driven shaft 17 on the reduced end 18 of which is mounted, between clamping plates 21 and 23, a cylindrical sizing portion 22. Said sizing portion 22 is of an outside diameter equal to the desired inside diameter of the finished piston ring or segment, and is of a length slightly less than the length of the helix 24 when compressed between the clamping plates 21 and 23. Compression lengthwise of the helix 24 is accomplished by turning up a nut 20 on the threaded portion 19 of the reduced end 18. When fully compressed, the flat faces 12 of the helix turns are held pressed together in abutting relationship, with the inner edges 14 held tightly against the outer surface of the arbor portion 22 and with the outer edges 13 forming the outer surface of helix 24.

While on the arbor 25, the outer surface of the helix 24 is processed to leave it smooth and fully cylindrical and of an outside diameter substantially that of the finished piston ring or ring segment when closed to circular form. This processing is accomplished by either a grinding or machining operation and is here illustrated as being done by a grinding wheel 26. As indicated above, if not required, this finishing step can be entirely omitted.

In the next step, with the helix 24 still mounted on the same arbor 25, or on a different but similar arbor, an outer layer of a wear-resistant material is sprayed onto the outer surface of the helix. As illustrated in FIG. 4, a spray gun 27 is used for this purpose. The material sprayed in the manner indicated by the spray 28 is preferably molybdenum but other high melting point, wear resistant metals such as tungsten, tantalum and osmium can be used, as will later be pointed out in greater detail. Commercially available spraying equipment, such as that offered for sale by Metallizing Engineering Company, Inc., Long Island, New York, can be used satisfactorily. The thickness of the coating, indicated by the reference numeral 29, can be controlled to within 0.001 inch.

Where such spraying equipment is used, and the metal selected is molybdenum, the molybdenum is supplied to the spray gun in the form of wire that is substantially pure molybdenum metal, having a melting point of about 4750° F. Since the principal oxide of molybdenum is a vapor at temperatures above about 1400° F., the molten material that hits the outer surface of the helix 24 and solidifies thereon to form the layer 29 is substantially pure molybdenum metal. As a result, good adherence of the layer 29 to the surface of the helix 24 is obtained. Said layer 29, it should be noted, is continuous over and co-extensive with the entire outer surface of said helix 24, and thus bridges the tightly abutting surfaces between adjacent turns of the helix.

In practice, it has been found advisable to apply a thicker coating of molybdenum than that which is to provide the desired thinness of the final coating on the piston rings or ring segments. Accordingly, if the final coating is to be 0.004 inch or less, the initial thickness of the coat-

ing 29 may be in the neighborhood of 0.008 inch and the excess can be removed by machining or grinding. As illustrated in FIG. 4, the excess thickness of coating is removed by a grinding wheel 26 or an abrasive belt to leave a final coating 29a of the desired thinness. The arbor 25 is rotated while the grinding wheel 26 is caused to traverse the length of the helix while being fed radially inwardly into grinding pressure relation therewith.

After the completion of the surface coating and grinding operations, the helix 24 is next severed lengthwise into individual rings or ring segments. This severing operation may be performed on the same or on a different arbor, but is illustrated as being carried out on the same arbor. For this purpose, the arbor sizing portion 22 has a longitudinal slot 30 extending the full length thereof. Similar slots 31 are formed in the end clamping plates 21 and 23 in alignment with the slot 30. Severing of the turns of the helix 20 is suitably effected by means of a thin grinding wheel or diamond disk 32 mounted upon a driven shaft 33. Individual rings, or ring segments 34, are thus formed with gaps 35 between their severed ends.

In the act of severing as described, or as a result of the severing operation in combination with the act of removing the individual rings 34 from the arbor 25, the continuity of the coating 29a across the points between adjoining turns of the helix 24 is broken to leave separate, sharp-edged, thin layers 36 of molybdenum on the respective individual rings 34. Such sharp-edged thin layers of wear-resistant material have better wall scraping properties in service than if such layers were formed with rounded surfaces or with surfaces that continued over the side surfaces of the ring or segment.

Also, molybdenum has been found to be superior to chromium plate as a facing material, since it is higher melting than electroplated chromium and is less liable to scuff the cylinder wall due to spot seizure between the metal of the ring and that of the cylinder wall at high temperature.

FIGURES 7 and 8 illustrate a typical manner of assembling rail rings such as the ring 34, made in accordance with my method. An articulated assembly ring, such as the expander-spaced ring 37 (FIG. 8), is shown in association with rail rings 34 mounted in the oil groove 38 of a piston 39 for sealing the piston as it reciprocates within the cylinder 40 of an engine block 41. For a more complete showing of this type of rail ring assembly and mounting, reference is made to Patent No. 2,768,038, commonly owned with this application.

As herein described, the high melting point, wear resistant metal used to coat the ferrous metal rings or segments is one selected from the group consisting of molybdenum, tungsten, tantalum and osmium. All of these metals have higher melting points than chromium and impart superior properties to the rings, or segments, better adapting them for their use as piston rings, or segments. In general, the same method that has been described for molybdenum can be used for spray coating with any of these other metals, but if tungsten is used, it is preferable to spray the tungsten by a plasma method under nitrogen to prevent oxidation.

In the case of a chromium plated rail ring, the edge surface of the rail ring will be found to be somewhat rounded, due to the fact that the plating continues around the edges themselves. In service, the resulting rounded edge surface tends to cause the rail ring to flop back and forth, much like a paint brush and allows the rail to ride over the oil. Consequently, the ring has an inferior scraping action as compared with the sharp-edged, metal coated rail rings of my invention. Furthermore, the rail rings herein described afford better oil control because of better sealing. Such better sealing is accomplished without any localized concentration of pressure, for the reason that the expanding pressure exerted by the ring against the cylinder walls is more uniformly distributed than heretofore.

I claim as my invention:

1. The method of making piston ring segments adapted for use as rail rings, which comprises:
  - forming a thin, flat ribbon of metal into a helical coil of a predetermined inner diameter,
  - applying end-wise pressure to said helical coil to press the flat faces of said ribbon into tightly abutting relationship with the thin edges thereof forming the inner and outer surfaces of said coil,
  - spray coating the resulting outer surface with a layer of a wear-resistant, high melting point metal that is continuous and coextensive with said outer surface of said helical coil, and that bridges the abutting thin edges of said ribbon,
  - removing any excess of said sprayed metal layer to obtain a final continuous layer of predetermined thinness,
  - severing said helical coil lengthwise thereof, and
  - freeing the resulting individual ring segments with re-

sultant breaking of said continuous coating layer to obtain ring segments each having a transverse gap and a thin, laterally sharp-edged outer layer of the coating metal.
